UNITED STATES PATENT OFFICE.

JOHN MILLER FLEMING, OF OTTAWA, ONTARIO, CANADA.

AUTOMATIC STOKER.

944,778.

Specification of Letters Patent. Patented Dec. 28, 1909.

Application filed November 23, 1908. Serial No. 463,983.

To all whom it may concern:

Be it known that I, JOHN MILLER FLEMING, of Ottawa, in the Province of Ontario, Canada, have invented certain new and useful Improvements in Automatic Stokers, of which the following is a specification.

My invention relates to improvements in automatic stokers, and the objects of my invention are to provide a simple and effective form of device which may be used to feed fine coal or other fuel on the top of the grate bars and boilers and to evenly distribute the same over the whole surface of the fire, and further to provide means for throwing the stoker into automatic operation, whenever the pressure of the boiler falls below a given amount, and to provide means for introducing air to increase combustion.

Further objects are to provide means for increasing the efficiency of the fuel and in raising steam in the boiler.

These objects are attained by the mechanism hereinafter described more fully in detail in the accompanying specification and drawings.

In the drawings, Figure 1 is a vertical section through an ordinary boiler equipped with my improved automatic stoker. Fig. 2 is a perspective view of the fuel bin of the stoker. Fig. 3 is a section along the line 2--2, Fig. 2. Fig. 4 is a sectional elevation illustrating the form of automatic regulating apparatus. Fig. 5 is a section through one of the bars 20. Fig. 6 is a sectional view partially broken away, through the controlling member on the line 6--6 Fig. 3.

In the drawings, like characters of reference indicate corresponding parts in each figure.

Referring to the drawings, A is the boiler of any suitable or desirable construction, including a bridge wall 10, grate bars 11 and ash pit 12.

While any type of grate bars might be employed that I illustrate herein is the form of hollow grate bar invented by me and more fully set forth and described in an earlier application, Serial No. 430862, filed May 2nd, 1908.

In accordance with the invention, the grate bars are contained in the masonry structure B, which projects forwardly of the front of the boiler and immediately above the top of the grate bar, a fixed fuel hopper C is provided, the said hopper extending over

substantially the entire surface of the grate bars, whereby the fuel fed from the same may be evenly distributed over the surface of the grate bars as hereinafter described.

This hopper may be supported upon the masonry structure B in any suitable manner, as by the brackets 13 on the side of the same, which support the hopper from the top 14 of the masonry structure. The bottom of this hopper is formed with a plurality of openings adapted to permit the passage of fuel, and being formed, in the embodiment illustrated, by a grating 15 having transversely extending apertures 16 between the bars, the bars themselves being triangular in cross-section with the angular edge uppermost.

Immediately below the grating 15 a movable controlling member D is provided having apertures therethrough which are adapted to coact with the apertures in the hopper to permit feeding of the fuel in determined quantities, according to the movement of the controlling member. In the embodiment illustrated, this controlling member covers the bottom of the hopper and is adapted to reciprocate on tracks 17 and 18, being supported from side tracks by suitable rollers 19. The apertures through this controlling member are regulated by means of a grating 20, the space between the bars of this grating 20 being equal to substantially one-half the distance between the bars on the grating of the hopper, and the angular edges of the bars extending downwardly. In this way, the number of times which the apertures in the fuel hopper will be opened for a given movement of the controlling members are increased.

In order to increase the efficiency of the fuel by the introduction of air into the space above the grate bars, I form the bars of the grating 20, hollow, the said bars being removably supported from the sides of the frame 50, by fitting into slots 51 on the sides of the frame, said frame and bars together constituting the controlling member D. Each of the bars is provided with a longitudinally extending passage way 52 open to the air at both ends and having a plurality of ports 53 opening downwardly on the under side through which the air may be discharged on to the top of the fire. In this manner, the air passing through the bar will be heated and discharged into the

space above the fire and will increase the efficiency of the fuel by promoting combustion.

The movement or reciprocation of the controlling member is effected automatically by any suitable source of power. In the form I have illustrated bell crank levers 21 are pivoted to brackets 22 on the outer side of the masonry structure B having the arms 23 pivotally connected to projections 24 on the controlling member and having the opposite arms provided with a plurality of perforations 25, to which the end of a link bar 26 may be pivoted, the opposite end of said link bar being connected to cranks 27 on the shaft 28 which is connected by a suitable gear 29 with a driving shaft 30 which is driven through the medium of a belt 31 and pulley 41 from a suitable source of power, such as a small reciprocating steam engine.

In practice, a battery of boilers are usually found adjacent to each other and where this is so, the same shaft 28 may extend across all the boilers having cranks 27 formed at intervals thereon, to which the link bars 26 are connected.

While the periods, during which the fuel shall be fed, may be regulated by hand, I prefer to use the automatic regulating device herein shown. This consists of a vertically disposed fluid cylinder E disposed within a bracket 44 connected by a pipe 33 with the top of the boiler and having its upper end closed by a piston 34 on a rod 35, the upper end of the rod having a cord or chain 36 connected thereto, which cord or chain is connected to a controlling device for the power driving mechanism and in form illustrated extends over a suitable pulley or pulleys 37 to the upper end of a lever 38, which is centrally fulcrumed to a fixed support 39 and has a lower bifurcated end 40 adapted to engage the belt to shift the same from the live pulley 41 to the loose pulley 32 provided on the same shaft. The piston rod 35 is normally retained in its lowermost position by means of weights 42 supported on a rod 43 extending through the bottom of the bracket 44 and connected to the bottom of the piston.

In the operation of the automatic regulating device, the steam under boiler pressure, normally maintains the piston 34 at a given position in the cylinder, in which position, according to the adjustment of the device, the lever 38 will maintain the belt on the live pulley. As soon as the pressure sinks below the determined amount, the piston 34, under the influence of the weights 42, will move downwardly, and this, through the cord or chain 36 will tilt the lever 38 and move the belt from the loose pulley to the live pulley, causing the shaft 28 to rotate, which will reciprocate the bell crank 21,

causing the controlling member D to reciprocate, and this will permit passage of the fuel whenever the opening in the connecting member registers with those in the fuel hopper.

The advantage of having the bars on the grating 20 smaller and closer together than those on the grating 15 is that for a given movement of the grating 20, an increased number of openings will be made, as compared with gratings having bars of equal size and equally spaced apart. This increased occurrences of the openings in grating 15 produces a most desirable and efficient sprinkling effect not to be secured if the upper and lower bars were of equal dimensions. The rate of movement of the controlling member may be regulated by adjusting the upward pivoting point of the link bar 26 in the perforations 25. As the apertures simultaneously open and only remain open for the time it takes the controlling member to move the width of the opening, the fuel, which is preferably, in a finely divided state, falls evenly and uniformly over the whole of the grate surface and thus the fire is always maintained uniform and fine powdered fuel can be burned to advantage.

In order to get the greatest possible advantage from the heat of the fuel, I provide a set of water coils F above the grate bars, these coils extending over the top and down a distance at each side and being connected at one end with a pipe 45 leading to the upper part of the boiler and on the other end with a pipe 46 leading to the lower part of the boiler. In this way, the cooler water from the lower part of the boiler is made to circulate through the pipe and be heated by the fire below the same.

It will be observed that the automatic regulation of the feeding means may be adjusted to cause the device to feed whenever the pressure falls below a given amount by varying the weights 42. It will be observed that as the fuel hopper is located above the fire it will be heated thereby and then the efficiency of the fuel will be increased by the prior heating as is well known. The results obtainable by my advice equal those obtainable by hand firing which it is recognized is possible as the fuel is spread uniformly over the grate bar surface.

As many changes could be made in the above construction, and many apparently widely different embodiments of my invention, within the scope of the claims, could be made, without departing from the spirit or scope thereof, it is intended that all matter contained in these specifications and drawings shall be interpreted as illustrative and not in a limiting sense.

What I claim as my invention is:—
1. In an automatic stoker, the combination

- with grate bars and masonry structure supporting the same having an aperture in the top thereof, of a fixed hopper, having apertures in the bottom thereof, brackets bearing 5 on the masonry structure and supporting the hopper in position above the aperture in the said masonry structure, a reciprocative controlling member supported on the masonry structure, and extending below the bottom 10 of the aperture and having apertures therein adapted to register with those in the hopper.
2. In an automatic stoker, the combination with the usual grate bars and masonry structure surrounding the same having an aperture in the top thereof, and parallel tracks embedded in the masonry structure at each side of the aperture, of a fixed hopper having apertures in the bottom thereof, brackets supporting the hopper from the masonry 15 structure, and a reciprocative member located below the hopper having apertures therein adapted to register with those in the hopper, and being provided with rollers adapted to engage the tracks embedded in 20 the masonry structure.
3. In an automatic stoker, the combination with the fire grate, of a hopper disposed over the same, having the bottom formed by a grating, a controlling member disposed below the grating and being formed with a like grating having the bars closer together than those in the grating on the hopper and means for reciprocating the controlling 25 member.
35. 4. In an automatic stoker, the combination with the fire grate, of a fuel hopper disposed over the same having the bottom formed by an open grating, a controlling member having a grating thereon adapted to abut the 40 grating on the fuel hopper, the space be-
- tween the bars on the hopper being a multiple of the space between the bars on the controlling member and means for reciprocating the controlling member.
5. In an automatic stoker, the combination with a fire grate, of a fuel hopper disposed above the same, a fuel controlling member at the bottom of the fuel hopper, said controlling member having an air conducting means which communicates with the space 45 above the fire grate and the open air whereby air may be introduced into the space above the fire grate to promote combustion.
6. In an automatic stoker, the combination with a fire grate, of a hopper disposed over 50 the same, a controlling member disposed below the hopper, said member being formed with a plurality of hollow bars having downwardly discharging ports, adapted to conduct a fluid and discharge the same over the 55 grate.
7. In an automatic stoker, the combination of a fixed fuel hopper having suitable side walls and a grating forming the bottom, thereof, comprising spaced inverted 60 bars V shaped in cross section, a reciprocating member located below the fuel hopper formed with a grating comprising bars, V-shaped in cross section of smaller dimensions and spaced apart a distance less than the 65 space between the bars of said hopper, and means for reciprocating the controlling member.

In witness whereof I have hereunto set my hand in the presence of two witnesses.

JOHN MILLER FLEMING.
